2 SHEETS—SHEET 2.

UNITED STATES PATENT OFFICE.

WILLIAM J. LITTLEHALES, OF DICKINSON, NORTH DAKOTA.

PNEUMATIC PUMP-DREDGE.

1,180,664.

Specification of Letters Patent.

Patented Apr. 25, 1916.

Application filed March 12, 1915. Serial No. 14,034.

To all whom it may concern:

Be it known that I, WILLIAM J. LITTLEHALES, a citizen of the United States, residing at Dickinson, in the county of Stark and State of North Dakota, have invented certain new and useful Improvements in Pneumatic Pump-Dredges; and I do hereby declare the following to be a full, clear, and exact description of the invention, such as will enable others skilled in the art to which it appertains to make and use the same.

This invention relates to pneumatic pump dredges, and has for its object to provide an apparatus of this nature which will be comparatively inexpensive to construct and more efficient and certain in action than those that have been heretofore proposed.

With these and other objects in view the invention consists in the novel details of construction and combinations of parts, more fully hereinafter disclosed and particularly pointed out in the claims.

Referring to the accompanying drawings forming a part of this specification in which like numerals designate like parts in all the views—Figure 1 is a diagrammatic side elevational view partly broken away of an apparatus made in accordance with my invention; Fig. 2 is a longitudinal sectional view partly in elevation of the parts shown in Fig. 1; Fig. 3 is an enlarged detail partly sectional view of the lower end of the apparatus shown in Fig. 2; Fig. 4 is a side elevational view of the parts shown in Fig. 3 but seen in a direction at right angles to the plane on which Fig. 3 is taken; Fig. 5 is an enlarged detail sectional view of the upper portion of the apparatus shown in Fig. 1; and Fig. 6 is a plan view partly in section of the parts shown in Fig. 5.

1 indicates any suitable pipe preferably made in sections joined together as by the flanges 2.

3 indicates a delivery of any suitable construction from the pipe 1 and 4 a pipe preferably located inside the pipe 1 adapted to convey air to a point near the lower end 5 of said pipe 1.

6 indicates any suitable pipe for supplying air to the system, 7 a valve controlling the admission of air to the pipe 4, 8 a pressure gage connected with the pipe 4 and 9 a valve rod extending through the pipe 4 from one end to the other and connected 55 with the valve 10 at the lower end of said pipe 4 as best shown in Figs. 2 and 3.

The upper end of the pipe 1 is closed by any suitable plug such as 12 and this said plug 12 may be provided with the internal sleeve or collar 13 screw threaded into the plug 12 and itself receiving the internal and external screw threaded sleeve 14 in which the screw threaded portion 15 of the pipe 4 fits. The extreme upper end of the pipe 4 is provided with the stuffing box 16 through which the valve rod 9 passes and the screw threaded plug member 12 is provided with the yoke like members 17 having a seat 18 through which said valve rod 9 also passes and on which rests a spring 20. The upper end of the valve rod 9 is provided with the thimble like member 21 against which the upper end of the spring 20 rests and in which fits the internal screw threaded thimble like member 22, as shown. The extreme upper end 23 of the valve rod 9 is screw threaded as shown and fits the interior of the said thimble 22, and also receives the locking member 24 to hold said rod 9 in its adjusted position against the compression of the said spring 20. The said extreme end 23 of the rod 9 is also provided with the hand wheel or other member 25 for adjusting said rod 9 up and down as will be readily understood. The rod 9 may be conveniently made in sections joined together as at 26, and it may be screw threaded at its extreme lower end 28 and joined to the valve 10, or it may be otherwise rigidly attached thereto.

The extreme lower end of the air pipe 4 is conveniently provided with the valve member 30 having the spider or bridge member 31 through which the lower end of the rod 9 passes and also provided with the valve seat member 32, screwed or otherwise attached to the said member 30 and preferably having the inclined valve seat 33 against which the valve 10 fits, as shown.

The parts just disclosed constitute in themselves an effective air lift pump, in that when the pipe 1 is lowered beneath the surface of water in a well or in the ocean, and air is admitted through the pipes 6 and 4 with a pressure sufficient to unseat the valve 10, the said air will escape upwardly beneath the surface of the water and force the water up through the pipe 1 and out of the delivery 3 in a well-known manner.

The dredge portion proper of my invention consists of the following parts: Connected to the air supply 6 is a second air

pipe 35 provided with a valve 36, and extending down beneath the extreme lower end 5 of the pipe 1, where it enters the air chamber 37, as shown. This said air chamber is conveniently formed of a separate casting fitting the extreme lower end or foot of the dredge and is conveniently provided with the rests or shoes 38 in order to form a convenient support for the chamber 37. The extreme lower end 5 of the pipe 1 is preferably flared as shown, and may be conveniently provided with a curved elbow like member 39 with a perforated bottom 40 communicating with the air chamber 37. The elbow member 39 is also conveniently provided with an extended lip member 41 projecting slightly beyond the upper portion of the elbow member 39 and also slightly beyond the mouth or delivery 42 of the said chamber 37. The chamber 37 is conveniently secured to the elbow member 39 as by the bolts 43, and the perforated bottom 40 is preferably inclined as shown and the orifices 44 are also preferably inclined with respect to the bottom 40 as illustrated, in order that the air may be directed upwardly into the pipe 1.

The operation of the dredge portion of the invention will be readily understood but may be briefly summarized as follows: When air under pressure is admitted from the source 6 into the pipe 35 it partly escapes from the chamber 37 through the orifices 44 and partly through the exit or mouth 42. That portion of the air escaping through the mouth 42 serves to stir up the sand, mud, mineral or other material being dredged, and to force it away from the extending lip 41, whereupon it meets with the resistance of the surrounding water and tends to curve backward into the mouth of the elbow member 39. In the meantime the lower end 5 of the pipe 4 is moved forward so that the lip 41 constantly seeks new material to be thus stirred up or dislodged and the action proceeds. As fast as the material thus stirred up is received into the elbow member 39 it is caught by the air leaving the orifices 44 and is forced upward along the pipe 1 and is discharged through the pipe 3 into a boat or any other receptacle that may be provided. Of course the suction created by the air leaving the valve 10 tends to draw the dislodged material surrounding the lip 41 into the mouth of the elbow, and therefore when a considerable volume of air is fed to the apparatus a large volume of material will be lifted.

It is evident that as stated above, when it is not desired to dislodge material at the bottom or when it is only desired to pump water or sand, air from the pipe 35 may be entirely cut off and air through the pipe 4 may be employed to operate the device as an air lift pump.

When operating the apparatus as a dredge however it is convenient to suspend it from any suitable apparatus, such as a derrick, not shown, carried by a boat and from which a line may be extended to a collar such as 50. And in order to conveniently drag the device over the bottom a second line 54 is attached to a collar 51 near the bottom member 5 to move it in one direction and a third line 55 may be attached to the other end 52 of the collar 51 to move it in the opposite direction, as will be clear from the drawings. The pipe 35 may be made in sections and joined together as at 57 and the pipe 4 may be likewise made in sections and joined together as at 58. It will thus be seen that by following the construction above disclosed I provide a dredge pump, which may employ any suitable air pressure and therefore may be made of great power and strength, while at the same time its lower end may drag over the bottom in deep water and thus bring up minerals, sand, mud or other material in a most efficient manner.

My improved dredge should be carefully distinguished from the dredges heretofore proposed, in that it provides air under pressure delivered through the pipe 35 to lift gravel, stones, etc., after they have been dislodged by the lip 42, and this said compressed air gives them an acceleration or imparts to them a velocity along with the ascending column of water, which takes them well into the influence of the second column of air under pressure delivered through the pipe 4, which further accelerates the water, gravel, stones, etc., and which already are moving at a considerable velocity, so that the said gravel, stones, etc., can be lifted to relatively great heights depending of course entirely upon the amount of air pressure in the respective pipes 4 and 35. In other words, when suction alone is employed on dredges as has been heretofore customary, the height to which the water itself can be lifted is limited, and heavy particles such as gravel, stones, etc., can only be lifted to much less heights. It results from this that in comparatively deep sea dredging for gold and other precious minerals the suction dredges are not adapted to bring up the minerals in a manner as efficient as is mine, even in shallow water, and the said suction dredges cannot operate at all in water as deep as my dredge operates when the pressure is increased. As a matter of fact, in suction dredges heavy stones, soon settle back to the bottom of the dredge while in my apparatus the same stones can easily be lifted from a depth of 200 feet of water and over. Further, owing to the fact that when the column of water has once been accelerated to a high velocity as it soon is in my dredge, owing to the multiple

air columns under pressure, this said water possesses considerable force in carrying the stones, gravel, etc., along with it, so that the momentum imparted to said stones is utilized in lifting the same well out of the dredge and into the boat or other receptacle provided for them. It therefore follows that owing to the multiple air lifts spaced apart along the dredge pipe 1 my dredge 5 operates to lift stone, gravel, etc., just as well in deep water as do suction dredges in comparatively shallow water, and that it will lift minerals from depths that suction dredges cannot lift at all.

10 The above mentioned accelerated action is facilitated by the annular space between the pipes 4 and 35 combined with the annular form of the compressed air discharge from around the valve seat 33 into said annular 15 space. In other words, the tapered valve seat 33 combined with the tapered valve 10, causes the compressed air to move upward and outward filling said annular space and striking the inside walls of the pipe 1, thus 20 accelerating the water, stones and gravel in the manner disclosed above. The said valve 10 may be adjusted through the means shown to that height above the perforations 25 44 that is found to produce the best results 30 on the material being dredged.

As a matter of fact a fair limit for dipper and bucket dredges is only about forty or fifty feet of water in practical use, whereas in my dredge two hundred feet and over is 35 easily reached, and minerals brought up as satisfactorily as in much more shallow water.

An important feature of the invention resides in the fact that the valve 10 is provided with the controlling spring 20, which keeps it normally seated when the pressure is not sufficient to overcome the force of the spring, and therefore keeps sand from settling in the lower end of the pipe 4. That 40 is to say, as is well known to those familiar with the operation of air lifting pumps, when pumping mud or sand the pipe 1 being full of material the sand will naturally settle toward the bottom when the 45 pump is stopped. It therefore follows that should the air be cut off in the pipe 4 a certain portion of the sand will be of course carried up into the pipe 4 which will settle at the bottom of the pipe 4 and clog it up 50 unless some means is taken to prevent it. The same action occurs to a greater or less extent when the pressure in the pipe 4 falls somewhat below the pressure of the head of water on the outside of the pipe 1. In other 55 words, when operating pumps of this kind if the pressure varies to any great extent in the pipe 4, sand is liable to stop up the bottom of said pipe 4 unless special precautions are taken and when such stoppage occurs it gives rise to a great deal of annoy-

ance and to expensive repairs. It is found not sufficient to merely place a valve at the bottom of pipe 4 which requires to be operated by hand because such a valve not being automatic it does not open and close 70 with the variations of pressure and therefore sooner or later the pipe 4 becomes stopped up and the pump refuses to work. On the other hand, by placing the valve 10 under spring pressure as is disclosed in this 75 application, the operation is perfectly automatic and, the lower end of pipe 4 is always closed to the admission of sand. That is to say, when the valve 10 is opened air is escaping past it, and no sand can enter, while when air is not passing the valve 10 the spring automatically closes the said valve and still no sand can enter. It results from this that a pump provided with an automatic valve such as 10 is not subject 80 to break downs and annoying stoppages which are experienced by the pumps here- 85 tofore proposed.

In order to regulate the pressure necessary to unseat the valve 10 I provide the adjusting hand wheel 25 on the upper end of the valve rod 9, and I further provide the locking nut member or lever 24 to hold the valve 10 under the particular pressure to which it has been adjusted. 90

It is obvious that those skilled in the art may vary the details of construction, as well as the arrangements of parts without departing from the spirit of my invention and therefore I do not wish to be limited to 100 the above disclosure except as may be required by the claims.

What I claim is:

1. In a pneumatic dredge, the combination of a conduit pipe for the dredged material having a downwardly flaring lower end, an elbow member on said lower end provided with a lateral receiving opening and with a downwardly inclined bottom extending past such opening to form a downwardly inclined projecting lip, said bottom being provided with a series of apertures inclined to direct air jets upwardly through said elbow member to said conduit pipe, an air chamber communicating with such apertures and provided with an exit for directing air under pressure against the lower face of said downwardly inclined lip, means for supplying air under pressure to said chamber, and means within the lower end of 110 said conduit pipe for directing air under pressure upwardly in the path of the air jets from such inclined apertures of said bottom.

2. In a pneumatic dredge, the combination of a conduit pipe for the dredged material having a downwardly flaring lower end, an elbow member on said lower end provided with a lateral receiving opening and with a downwardly inclined bottom ex- 115 120 125 130

tending past such opening to form a downwardly inclined projecting lip, said bottom being provided with a series of apertures inclined to direct air jets upwardly 5 through said elbow member to said conduit pipe, an air chamber communicating with such apertures and provided with an exit for directing air under pressure against the lower face of said downwardly inclined 10 lip, an air pipe within the lower end of said conduit pipe for directing air under pressure upwardly in the path of the air jets from such inclined apertures of said bottom, means for supplying air under pressure to 15 said air pipe and bottom chamber, and independent means for controlling such air supply to said pipe and chamber.

3. In a pneumatic dredge, the combination of a conduit pipe provided with a flar-

ing lower end, means for directing a series 20 of air jets into said flaring end for feeding the dredged material thereto, an air pipe opening within the lower end of said conduit pipe for directing air under pressure upwardly in the path of such series of air 25 jets, an air valve controlling the opening of said air pipe, adjustable means for automatically closing said air valve at any pre-determined pressure within said air pipe, and means accessible at the upper end of 30 said conduit pipe for adjusting said automatic valve-closing means.

In testimony whereof I affix my signature, in presence of a witness.

WILLIAM J. LITTLEHALES.
